HANDLE FOR MATTRESSES

Application filed October 31, 1927. Serial No. 229,918.

This invention relates generally to mattress making, and especially to a form of handle which is applied to the sides of the mattress.

5 The first object of this invention is to provide an exceedingly simple and efficient form of handle by means of which a mattress can be readily lifted or moved regardless of its dimensions or style of construction.

10 The second object is to provide a handle which will at once be of good appearance and at the same time have sufficient strength for the purpose intended.

15 The third object is to facilitate the location of the handles on the mattress sides by making their outer surface of a contrasting color with relation to the ticking of the mattress.

20 These objects are accomplished in the manner set forth in the following specification as illustrated in the accompanying drawing, in which:

25 Figure 1 is a perspective view of a mattress having the handles applied to one side thereof. Figure 2 is a side elevation of the handle with a portion of its finished portion broken away to show the strong lining. Figure 3 is an enlarged section through the edge of the mattress showing the manner of attaching the handle to same. Figure 4 is a phantom view of the side of a mattress shown partially in perspective for the purpose of better showing the manner in which the handle is attached to the mattress.

30 Similar numbers of reference refer to similar parts throughout the several views.

35 Referring in detail to the drawing. In order to illustrate this invention there is shown the usual form of mattress consisting of the top 10, the ends 11 and the sides 12 around which are formed the roll edges 13 and 14, in which it will be noted that the ends 15 of the roll 13 are sewed internally, while the ends 16 of the roll edges 14 are sewed externally. The usual roll edge stitching 17 and 18 is also indicated.

40 Turning now to the handle itself it will be seen to consist of an H-shaped member comprising the upright body portions 19 and the cross strap 20, which, in reality, forms a han-

dle. It is preferable to round the corners 21 at the junction of the members 19 and 20.

45 The front 22 of the handle is made of highly finished material which need not have much tensile strength. Directly behind the front 22 is a similarly shaped piece of fabric 23 which forms a lining and provides the necessary strength for the handle.

50 In the manufacture of the handle it is secured to the front 22 by the stitching 24 and 25. When assembled with the mattress the ends 26 of the handle are sewed between the ends 15 of the roll edges 13 and the ends 27 are sewed between the ends 16 of the roll edges 14.

55 In completing the ticking the ends 27 of the handle are, of course, sewed in last, and when the handle is attached to the mattress the roll edges do not yet exist; in fact are not formed until after the filling is put into the 60 mattress. The roll edge stitching 17 and 18 also catches the ends 26 and 27 and transfers the strains from the handle directly through the roll edges, making same extremely strong and of good appearance.

65 Prior to the filling of the mattress: in fact during the earliest stages of the assembly of the mattress itself the body members 19 are themselves secured by means of rows of vertical stitchings 28 to the sides 12 of the mattress, and while these attach the body portions 19 to the side ticking 12, they, in reality, do not withstand much of the strains coming from the handles, since there will be sufficient yielding of the sides 12 to allow a transfer of 70 the strains to the roll edge stitching 17 and 18, although, of course, their portion of the fastenings between the members bears its 75 portion of the strain.

80 As above suggested, the material in the front 22 is highly finished and a contrasting color, which makes the handles easily discernible on the sides of the mattress instead of difficult to locate, as is ordinarily the case.

85 Again, the highly finished material is used to cover the less attractive lining 23, which must possess the strength to do the work for which the handles are intended.

90 We are aware that many forms of handles have been constructed for mattresses; we 95

therefore do not claim such devices broadly, but we do intend to cover all such forms and modifications as fall fairly within the appended claim.

5 We claim:

5 A mattress handle consisting of an **H**-shaped member of finely finished fabric of negligible strength and a similarly shaped lining of strong material having its edges 10 stitched to said front along its entire exposed area and having the upper and lower ends of the **H**-shaped members caught between the seams of the roll edges; and having the outermost portion of the handle contrasting in 15 color with said mattress ticking.

JACOB GOLDEEN.
